UNITED STATES PATENT OFFICE.

WILLIAM J. LA ROSE, OF NORTH TROY, NEW YORK.

COLLAR.

Application filed May 24, 1927. Serial No. 193,797.

The object of the invention is to provide a collar in the form of the conventional soft collar but equipped with means which will ensure its retaining its shape and prevent curling up at the lower edges; to provide a construction of collar in which the stiffening means may be incorporated as an element of the collar in the manufacture of the same and which, in the laundering of the collar, will not interfere with the effective performance thereof; and to provide a device of this character which may be easily and cheaply manufactured and therefore marketed at small cost.

With this object in view, the invention consists in a construction and combination of parts of which a preferred embodiment is illustrated in the accompanying drawings, wherein:

20 Figure 1 is a perspective view of a collar embodying the invention.
Figure 2 is a plan view of the outer fold showing the manner in which the stiffener is applied.
25 Figure 3 is a similar view of the outer fold after turning.

Figure 4 is a sectional view on the plane indicated by the line 4—4 of Figure 1.

The stiffener 10 is carried at the lower and front edges of the outer fold 11 of the collar 12, the outer fold consisting of a plurality of plies, for example, two, as indicated at 11^a and 11^b and these at the front edges and at the lower edge are united as by a button-hole stitch 14. The stiffener which comprises two L-shaped sections 15 is laid against the face of the collar sufficiently within the connected edges of the two plies to permit the marginal edges being folded over it, as indicated in Figure 2, an adhesive being employed to secure the stiffener in place. The two sections 15 are connected at the back of the collar by a coupling or fastening member 17. With the marginal edges folded over the stiffener 5 and secured to the body of the fold, the stiff-

ener is thereby enclosed and then the two plies are turned so as to dispose the stiffener between them as indicated in Figure 3, when the stiffener lies at the two front edges of the fold and at the lower edge. The inner fold 50 18 of the collar is then applied in the usual way.

The stiffener is made of a material commercially known as "Chalmite" which is a composition of plant fibre mixed with glue 55 or other suitable binder and rolled or compressed into the form of sheet material. The material is soft and pliable and capable of standing in storage for an indefinite length of time without injury.

The outstanding characteristic of the material of the stiffener in its present adaptation is that when it is necessary to wash the collar, the immersion of the same in the water results in the stiffener becoming very 65 pliable so that the collar may be thoroughly scrubbed and thereafter dried and ironed, when the material of the stiffener reacquires its stiffness.

The invention may be incorporated in the 70 form of collar commonly known as the lock-stitched top, where it functions in the same manner as in the illustrated embodiment.

The invention having been described, what is claimed as new and useful is:

75 The method of constructing a double fold soft collar which consists in providing a duality of plies for the outer fold, stitching said plies together at the ends and one side edge, applying a stiffener along the stitched edges but inset from the same, folding the stitched edges over the stiffener and securing them to the body portion of the plies, and finally turning the plies inside out to dispose the stiffener at the bottom and front edges 80 85 of the fold.

In testimony whereof he affixes his signature,

WILLIAM J. LA ROSE.
